UNITED STATES PATENT OFFICE.

FRANK A. KUCERA AND CHARLES F. RUBEL, OF CHICAGO, ILLINOIS, ASSIGNOR TO UNION SPECIAL MACHINE COMPANY, OF CHICAGO, ILLINOIS, A CORPORATION OF ILLINOIS.

MACHINE FOR CLOSING PAPER SACKS.

Application filed April 10, 1924. Serial No. 705,570.

To all whom it may concern:

Be it known that we, FRANK A. KUCERA and CHARLES F. RUBEL, citizens of the United States, residing respectively, at Chicago, in the county of Cook, State of Illinois, have invented certain new and useful Improvements in Machines for Closing Paper Sacks, of which the following is a description, reference being had to the accompanying drawing and to the figures of reference marked thereon.

The invention relates to new and useful improvements in sewing machines, and more particularly to a sewing machine which is adapted to stitch and close a paper sack.

An object of the invention is to provide a machine for closing paper sacks wherein the fabric is placed along the walls of the sack at the mouth thereof as it is stitched, so that the stitches for closing the sack pass first through the fabric and then through the paper walls at the mouth of the sack so that the fabric affords an anchorage for the stitches.

Another object of the invention is to provide a machine of the above type with a trimming mechanism having the trimming blade thereof operating in advance of the stitching mechanism so that the walls at the mouth of the sack are trimmed prior to the closing of the sack.

A further object of the invention is to provide a machine of the above type wherein the fabric which serves as an anchorage for the stitches extends about the trimmed sides of the sack, thus enclosing the mouth of the sack.

A still further object of the invention is to provide a machine of the above type having means for cutting the threads between successive sacks, wherein the cutting blade cutting the threads and the trimming blade for trimming the paper at the mouth of the sack are both operated by the same connection with the moving part of the sewing mechanism.

A still further object of the invention is to provide a machine of the above type wherein the fabric passes through a folder of the English binder type, which folder is located close to the work supporting arm of the machine and is yieldingly mounted so that it may be raised or moved away from the parts of the machine to permit the ready

removal of the cover plate for the operating parts within the arm of the machine.

A still further object of the invention is to provide a machine of the above type with a reel for supporting the strip roll from which the fabric is taken, and wherein said strip roll is mounted on a bracket carried by the arm of the machine, so that the entire machine with its fabric support is a unit, and can be raised and lowered as a unit.

These and other objects will in part be obvious and will in part be hereinafter more fully disclosed.

In the drawings which show by way of illustration one embodiment of the invention—

Figure 1 is a front view of a portion of a filled bag closing machine having our improvements applied thereto;

Fig. 2 is a side view of the sewing head from the side of the machine entered by the bag to be closed;

Fig. 3 is a side view of the machine at the other side from that shown in Fig. 2;

Fig. 4 is an enlarged view showing the end of the cylinder and the stationary cutter of the thread cutting mechanism;

Fig. 5 is an enlarged view of the end of the cylinder and the parts adjacent thereto as viewed from below;

Fig. 6 is a perspective view of the presser foot as viewed from above;

Fig. 7 is an enlarged front view of the work cylinder, also showing the presser foot, the trimming mechanism and the strip guide associated therewith;

Fig. 8 is a front view of the end of the work support with parts broken away to show the operating connection for the thread cutter and trimming mechanism, also showing diagrammatically the fabric strip passing through the machine, and

Fig. 9 is a section on the line 9—9 of Fig. 7.

The invention is directed broadly to a filled bag closing machine which is adapted for closing the mouth of a paper sack. It is a well known fact that paper easily tears and is not readily adapted for a sack closed by stitching. Prior to our invention, it has been proposed to provide a fabric strip which may be used as an anchorage for the stitches so that the mouth of a bag may be stitched for closing, and the stitches thus

anchored by the fabric serve to hold the mouth closed under the strain of handling.

The patent to Weatherwax No. 962,934, granted June 28, 1910, shows such a bag.

5 This Weatherwax patent, however, is a specially constructed bag in which the fabric strip is made a part of the bag before it is filled. The present invention has to do with a bag of the type above referred 10 to and includes a machine wherein the fabric strip is applied to the bag as it is stitched, so that the paper bags may be made up as usual, filled and fed into the machine without any thought or care of the attachment 15 of the fabric strip thereto. The machine includes a trimming mechanism which operates to trim the sack in advance of the needle so that the trimmed side edges will be a definite distance above the line of stitching. 20 A fabric guide of the English binder type is arranged to direct a strip of fabric into the machine and fold the same about the trimmed side faces of the mouth of the bag and in such a way that the needle will 25 pass through a side wall of the folded strip first, and then through the paper walls of the bag, and the fabric strip will afford an anchorage for the stitches so that the threads will not tear through the paper. The im- 30 proved filled bag closing machine includes means whereby the needle and the bag to be closed have a relative step by step movement during the stitching of the bag for closing the same. This may be brought about by 35 the movement of the bag itself, on a suitable conveyor, a supporting carriage or the like, or by the movement of the sewing head.

In Fig. 1 of the drawings we have shown a portion of a filled bag sewing machine 40 wherein the paper bag is indicated at 1. A support for the bag is indicated at 2. As noted above, said support may be of the traveling belt type as shown in the patent to Bigelow No. 895,311, granted December 1, 45 or it may be a stationary support and the sewing head mounted to travel back and forth relative to the support. The sewing head of the improved filled bag sewing machine except for the trimming mechanism 50 applied thereto is of the type shown in the patent granted to D. S. Seymour, July 6, 1915, No. 1,145,620 and includes a work sup- 55 porting cylinder 3 which is carried by a standard 4. Said standard is also provided with an overhanging arm 5 in which a needle bar 6 is reciprocated by the aid of a needle lever 7. Said needle lever 7 is connected to the needle bar 6 by means of a link 8. At the lower end of the work sup- 60 porting cylinder there is a throat plate 9 provided with slots through which the feed dog 10 operates to feed the parts being stitched. This feed dog and its operating mechanism is similar to that shown in the 65 Seymour patent above referred to, and de-

tail description thereof is not thought necessary. The bag is held against the throat plate by means of a presser foot 11 carried by a presser bar 12 mounted in the head of the machine. The presser foot is pivoted at 13 to a supporting shank carried by the presser bar 12. Said presser foot has a relatively long turned-up extension 14 at its forward end so as to aid in the directing of the bag between the presser foot and the throat plate. The work supporting cylinder is rounded off at 15 so as to cooperate with the extension of the presser foot in the directing of the bag to the stitching mechanism. 75

As has already been noted, the paper sack as it passes beneath the presser foot is trimmed by means of a trimming mechanism. This trimming mechanism includes a movable trimming blade 16 which cooperates with a stationary blade 17 formed as a part of the throat plate (see Fig. 8 of the drawings). The movable blade is carried by a lever 19 which is pivoted at 20 to a depending bracket 21 carried by the head 80 of the machine. The end of the lever 19 opposite the trimmer blade is pivoted at 22 to a link 23 which in turn is pivoted to an arm 24 extending from the thread cutter lever 25. This thread cutter lever and its 85 operating mechanism will be referred to more in detail later. The trimmed off portion of the bag engages a strip deflector 26 which deflects said trimmed off strip away from the stitching mechanism. 90

It is rather difficult to bring the extreme edges of the side walls of the bag together, and particularly so of a paper sack. When the trimming mechanism is used, however, for trimming these side walls on a definite 95 line relative to the stitching mechanism, it is immaterial whether the edges of the side faces of the bag are at the same height or not when the bag goes into the machine. All that is necessary is that these edges shall 100 be above the trimming line so that both the side walls will be trimmed and thus leave the trimmed portions clamped by the presser foot and in such position that a needle will pass readily through the same 110 as the feed carries the bag to the stitching mechanism. 115

A needle is indicated at 6^a in the drawings, and cooperating with said needle is a thread carrying looper 27 which is preferably of the 120 construction shown in the Seymour patent above referred to. Between the trimming blade 16 and the needle 6^a is a guide 28 of the English binder type, which is adapted to guide, fold and invert the fabric strip. 125 This guide 28 is located in a recess 29 in the throat plate, and a recess 30 in the presser foot and extends both to the front and rear of the plane of the throat plate, so that the mouth of the bag passing along the face of 130

the throat plate, will pass through the U-shaped channel on the forward end of the binder. The fabric strip is indicated at 31 in the drawings. Said fabric strip is wound 5 on a spool or reel 32 pivotally supported by a rearwardly extending arm 33 in turn mounted on a standard of the machine. The strip runs underneath the arm of the machine as clearly shown in Fig. 1, and then 10 across the guiding post 34 into the guide 28. The strip as it leaves the guide is inverted as clearly shown in Fig. 8, and the side walls of the bag pass into the inverted strip in such a way that the needle will 15 form a line of stitches 35 through the fabric strip and through the side walls of the paper sack. Thus it is that the fabric strip serves as an anchorage for the stitches and also serves as a clamping means for clamping the 20 side walls of the sack one against the other, and thus holding the bag closed. As shown in Fig. 2, it will be noted that this guide 28 is in front of the removable cover plate 36. The guide is carried by a shank portion 37 25 mounted on two bolts 38 and 39 which extend through slots in the shank. While these bolts support the guide, they do not clamp it. It is free to move on the bolts. A spring 40 bears against the left-hand end 30 of the shank and forces the guide toward the cylindrical work support. The purpose of this yielding mounting of the guide is to permit the guide to be raised slightly to withdraw or insert the cover plate 36. A guard 35 wire or bar 41 is secured to the presser foot and shields the needle and the trimming blade so that the operator will not be caught by these parts during the operation of the machine. After the bag has been stitched, 40 it passes from the machine and the machine forms a chain of stitches extending from one bag to the next bag. This chain of stitches may be caused to enter a slot 42 in rear of the needle 6^a (See Fig. 8). At the rear end 45 of this slot there is a cutter 43 carried by a cutting lever 25 referred to above. Said lever is pivoted at 44 to a lug carried by the cylindrical work supporting arm. The lever is oscillated by means of a link 45 which is 50 pivoted at 46 to the lever, and is pivoted at 47 to the arm 48 (see Fig. 8). Said arm 48 is in turn oscillated by a moving part of the feeding mechanism of the machine. This cutting member is similar in construction 55 to the thread cutting member of the Seymour Patent No. 1,170,349 granted February 1, 1916, and further description thereof is not thought necessary. While, in the present invention, this cutting lever performs the function of cutting the thread, it 60 also preferably performs another function, that is, it operates to cut the tape which is stitched to the mouth of the bag during the closing thereof. In other words, the tape, 65 together with the stitches will run from one bag to another, and the severing knife severs both the tape and the stitching threads. The cutting blade 43 cooperates with a stationary cutting blade 49 which is clamped in a groove in the work support by means of a screw 50. An oiling pad 51 is located directly in rear of the cutting blade 43, and the movable blade is pressed against the stationary blade by means of a spring 52. As 70 shown in the present embodiment of the invention, the cutting blade which severs the stitches and the tape between filled closed sacks and the trimming blade which trims the walls of the sack, are both operated from the same shaft on the arm of the sewing head. It will be understood, of course, that these members may be otherwise operated without departing from the spirit of the invention as set forth in the appended claims. 75

The sacks are filled in any desired manner, and are placed on the support therefor and fed to the stitching mechanism; or placed on a suitable support such as weighing scales or the like, and the sewing mechanism fed across the top of the stationary sack. The 80 side walls of the sack are brought together and are directed between the presser foot and the throat plate so that said side walls will be trimmed by the trimming member. The 85 trimmed edges passing the trimming blade will enter the fabric guide and the fabric guide will fold the strip of fabric about the side edges so that the fabric and the trimmed edges of the sack will be entered by the needle and a line of stitches formed 90 parallel with the trimmed edges and anchored in the fabric strip so as to close the bag. The bags after they are closed pass one after the other out from beneath the presser foot and the chain of stitches connecting adjacent bags will drop into the path of the 95 thread cutter 43 which is continuously reciprocating.

It is obvious that minor changes may be made in the details of construction and the 100 arrangement of the parts. The essential features consist in the trimming of the side walls of the bag prior to the closing of the same and the placing of the fabric strip about the mouth of a paper sack so as to 105 form a proper anchorage for the stitches.

Having thus described the invention, what I claim as new and desire to secure by Letters Patent, is—

1. A sewing machine for closing a filled sack comprising a support for the filled sack, a sewing head overhanging the support and including stitching mechanism having a horizontally reciprocating needle, and a trimming mechanism having a trimming blade operating in front of and above said needle to trim and even the side walls of the sack prior to the stitching of said side walls together for closing the sack. 115
2. A sewing machine for closing a filled 120

- paper sack comprising a support for the filled sack, a sewing head overhanging the support and including stitching mechanism having a horizontally reciprocating needle, and a trimming mechanism having a trimming blade operating in front of and above said needle to trim and even the side walls of the sack prior to the stitching of said side walls together for closing the sack, 10 and means operating between the trimming blade and the needle for placing a fabric along each side of the mouth of the sack after it is trimmed and prior to the stitching of the sack so that the stitches will 15 pass through the fabric strip and the side edges of the sack thereby closing the sack.
3. A sewing machine for closing a filled paper sack comprising a support for the filled sack, a sewing head overhanging the support and including stitching mechanism having a horizontally reciprocating needle, and a trimming mechanism having a trimming blade operating in front of and above said needle to trim and even the side walls 20 of the sack prior to the stitching of said side walls together for closing the sack, a strip guide located between the trimming blade and the needle for guiding and folding a strip of fabric about the trimmed side walls of the mouth of the sack and positioning said strip so that the needle will 25 pass through the strip as well as the side walls of the sack and the stitches will be anchored in the fabric strip.
4. A sewing machine for closing a filled paper sack comprising a support for the filled sack, a sewing head overhanging the support and including stitching mechanism having a horizontally reciprocating needle, 30 and a trimming mechanism having a trimming blade operating in front of and above said needle to trim and even the side walls of the sack prior to the stitching of said side walls together for closing the sack, a strip guide located between the trimming blade and the needle for guiding and folding a strip of fabric about the trimmed side walls of the mouth of the sack and positioning said strip so that the needle will 35 pass through the strip as well as the side walls of the sack and the stitches anchored in the fabric strip, and means for yieldingly supporting said strip guide so that it may be

raised vertically to facilitate the removing of the cover plate of the machine. 55

5. A sewing machine for closing a filled paper sack comprising a support for the filled sack, a sewing head overhanging the support and including stitching mechanism having a horizontally reciprocating needle, and a trimming mechanism having a trimming blade operating in front of and above said needle to trim and even the side walls of the sack prior to the stitching of said side walls together for closing the sack, and means operating between the trimming blade and the needle for placing a fabric along each side of the mouth of the sack after it is trimmed and prior to the stitching of the sack so that the stitches will 60 pass through the fabric strip and the side edges of the sack thereby closing the sack, and a severing mechanism located in rear of the stitching mechanism and operating in a plane at right angles to the line of feed for severing the fabric strip and the 65 enchain stitches extending between the stitching mechanism and the closed bag.

6. A sewing machine for closing a filled paper sack comprising a support for the filled sack, a sewing head overhanging the support and including stitching mechanism having a horizontally reciprocating needle, and a trimming mechanism having a trimming blade operating in front of and above said needle to trim and even the side walls of the sack prior to the stitching of said side walls together for closing the sack, a strip guide located between the trimming blade and the needle for guiding and folding a strip of fabric about the trimmed side walls of the mouth of the sack and positioning said strip so that the needle will 70 pass through the strip as well as the side walls of the sack and the stitches anchored in the fabric strip, and a severing mechanism located in rear of the stitching mechanism and operating in a plane at right angles to the line of feed for severing the fabric strip and the 75 enchain stitches extending between the stitching mechanism and the closed bag.

In testimony whereof, we affix our signatures.

FRANK A. KUCERA.
CHAS. F. RUBEL.
